REVOLVING SEAT

Thomas D. Owler, Chicago, Ill., assignor, by
mesne assignments, to S. Karpen & Bros., a
corporation of Illinois

Application June 17, 1935, Serial No. 27,091

2 Claims. (Cl. 155—96)

This invention relates to a revolving seat and more particularly to a revolving seat-support. The invention is especially useful in connection with transportation seats.

5 An object of the invention is to provide a revolving seat, suitable for railway cars, buses, and other transportation uses, in which the parts are reduced to a minimum and in which the main parts may be readily separated when desired. A
10 further object is to provide a seat-supporting structure of extremely simple construction in which interchangeable parts may be used to adapt the support for seats of varying sizes. Other specific objects and advantages will appear as the specification proceeds.

15 The invention is illustrated, in a preferred embodiment, by the accompanying drawing, in which—

Figure 1 is a plan view of a seat-supporting structure embodying my invention; Fig. 2, a side view in elevation; Fig. 3, a transverse sectional view, the section being taken as indicated at line 3 of Fig. 2; Fig. 4, a broken detail sectional view, the section being taken as indicated at line 4 of Fig. 1; and Fig. 5, a broken sectional detail view, the section being taken as indicated at line 5 of Fig. 1.

20 In the illustration given, A designates a base member; and B, a rotatable member carried by member A.

25 The base A may be of any suitable construction. I prefer to form it of aluminum alloy because of the lightness of the structure, although other suitable metal may be employed. In the illustration given, the base A is provided with a base flange 10 which may be bolted to the bottom of a car. Integrally formed with base flange 10 is a cylindrical flange or neck 11. Integrally formed with neck 11 at its upper side is a wide horizontal flange 12. A series of spaced ribs 13 are formed 30 integrally with the neck 11 and flange 12 to form supports for the flange 12. On its inner side, the neck 11 is preferably cut away at 14 to provide a space between the member A and the rotatable member B.

35 The rotatable member B may also be of any suitable construction. It is preferably formed of a heat-treated aluminum alloy, but any other suitable metal may be employed. The member B is provided with a deep tubular neck 15 which is telescopically received within neck 11 of base A. The tubular flange or neck 15 is also cut away on its outer side at 16, as shown more clearly in Fig. 5, so as to provide with the cut-away portion 40 of neck 11 a space between the parts 11 and

15, thus reducing the contacting area between the parts. The member B is also provided with a horizontal flange 17 resting upon flange 12. Flange 17 is cut away on one side to provide shoulders 18, as shown more clearly in Fig. 1, 5 adapted to engage the lug 19 carried by flange 12. The cut-away portions about the periphery of flange 17 and between shoulders 18 permit the rotatable member B to be rotated through the arc of a half circle. 10

20 Seat-supporting arms 20 are carried by the rotatable member B. The arms may be of different lengths to support different sized seats. Preferably, the arms are constructed as shown more clearly in Figs. 1, 2 and 4. As shown more clearly 15 in Fig. 4, each arm 20 is provided with a flat bottom flange 21 which rests upon the horizontal flange 17. The flange 21 at its rear side is turned downwardly to form a segmental flange 22 which is received within flange 15 of member B. The horizontal flange portion 21 is inclined upwardly as it extends beyond flange 17 to provide an inclined wall 23. The inclined wall 23 terminates in a horizontal circular support 24 which is perforated to receive a bolt (not shown) by which the arm may be secured to a seat structure. To reinforce each of the arms, I provide a vertical flange 25 which runs centrally along flanges 21 and 23, as shown more clearly in Figs. 1 and 2. The flanges 21 and 22 are secured to the neck 15 25 and flange of member B by removable bolts 26 30 and as shown more clearly in Fig. 4.

35 Any suitable locking means for releasably connecting the rotatably related parts of the structure may be employed. In the illustration given, the neck 11 of base A is apertured at 27 to receive locking pin 28. The inner tubular member 15 of member B is provided with a pair of apertures 29 through which pin 28 may extend. The locking pin or bolt 28 is housed within a tubular casing 30 which is provided with a circular flange 31 bolted to the circular flange 11. A spring 32 is housed within the casing 30 and extends about a reduced end portion 33 of bolt 28. The lower side of casing 30 is provided with a slot 34. 40

45 To reciprocate the bolt 28, I provide a treadle member 35 which is pivotally secured to a lug 36 carried by the circular flange 11 and a bell-crank arm 37 extends upwardly through the slot 34. The upper end of arm 37 is formed in the shape 50 of a ball 38 which is received within a recess 39 of pin 28. The outer end of the treadle arm 35 is provided with a wide flange 40 which is inclined at the angle shown in Fig. 2. The inclination of the treadle flange 40, as illustrated, 55

enables the operator to conveniently swing the bolt in and out of locking position.

In the operation of the device, assuming that the parts are in the locked position shown in Figs. 3 and 5, and it is desired to reverse the position of the seat, the operator places his foot on treadle flange 40 and thereby retracts bolt 28 from engagement with opening 29 of the circular flange 15. The rotatable member B may then be swung about in a semi-circle, the pin or bolt 28 riding against the outer periphery of flange 15. The engagement of lug 19 with shoulder 18 causes the rotation of the seat to stop when it is fully reversed and at the same time, pin 28 automatically slips into opening 29 under the pressure of spring 32. When it is desired to remove the seat in order that the cushion parts, etc. may be cleaned, it is only necessary for the operator to depress treadle 35 and then lift the seat structure with rotatable member B away from the base structure A. Thus in a very brief time, the seats within a railway car may be removed, leaving only the base structures in the car. New seats can be readily installed in place of the removed seats if desired, it being necessary only to withdraw pin 38 by pressing on treadle 35, while the neck 15 of the rotatable member B is dropped within circular flange 11. If it is desired to support a larger seat structure or a seat structure of a different shape upon rotatable member B, this may be readily accomplished by removing the supporting arms 20 and replacing them with supporting arms of different lengths.

The new structure eliminates a large number of parts formerly thought necessary for a seat-supporting structure, while providing a sturdy construction of extremely few parts, the main parts of which may be readily separated or interchanged.

While I have shown by way of illustration a specific structure, it will be understood that changes can be made with respect to many of the details thereof without departing from the spirit of my invention. The foregoing detailed description has been given for clearness of understanding only, and no unnecessary limitations should be understood therefrom, but the appended claims should be construed as broadly as permissible, in view of the prior art.

I claim:

1. A revolving seat-support comprising a base equipped with a tubular flange and a horizontal flange at the top of said tubular flange, a rotatable member having a horizontal flange resting on said first-mentioned horizontal flange and a tubular flange received within said first-mentioned tubular flange, and seat-supporting arms having their inner ends turned downwardly, said arms being secured both to the top side of the horizontal flange and to the inside of the tubular flange of said rotatable member.

2. A revolving seat-support comprising: a base having a tubular flange and a horizontal flange at the top of said tubular flange; a rotatable member having a horizontal flange resting on said first mentioned horizontal flange and a tubular flange received within said first mentioned tubular flange; and seat-supporting arms including flat bottom flanges having their inner ends turned downwardly and including also vertical flanges extending longitudinally of the arms and above said bottom flanges, said bottom flanges being secured both at the top side of the horizontal flange and to the inside of the tubular flange of said rotatable member.

THOMAS D. OWLER.
